UNITED STATES PATENT OFFICE.

WESLEY WAIT, OF NEWBURGH, NEW YORK.

INTERLOCKING JOINT FOR METALLIC FRAMES.

Application filed March 31, 1927. Serial No. 180,013.

This invention relates to improvements in interlocking joints for columns and girders, such as are employed in the construction of heavy metallic frames used to sustain excessive loads, as in the foundation frames for massive buildings, pinch-frames for mine tunnels, shoring for subways and the like. In such constructions the frame units are ordinarily joined together by bolting and riveting. In the employment of such methods much trouble has been experienced, owing to the difficulty in obtaining a uniform setting of bolts and even clinching of the rivets. Where the bolts are not uniformly set up, or the rivets are unevenly clinched, so that the stress of the load is carried by only a few of them, then there is a tendency to shear these few bolts to the detriment of the joint. Furthermore, when a joint is formed by bolts or rivets, it is difficult to determine by inspection whether the joint is faulty or not.

The principal object of the instant invention is to avoid the use of bolts and rivets and to provide a joint by shaping the ends of the columns and girders so that they can be joined in an interlock to form the joint. The ends of frame units are shaped to conform with predetermined patterns designed for ready engagement and even distribution of the load stress between the engaged parts. The cutting and shaping of the frame members to provide the interlocking joint can be done at a central place equipped with machinery for quantity production to be furnished as stock material. In forming the joint it is only necessary to position the members in interlocking relation. This is a particular advantage where the joint is made in a restricted space—a mine tunnel, for instance—cramping the use of riveting machines and bolting implements. After a joint has been formed all its parts are exposed for inspection so that faulty work can be readily detected.

The interlocking joint for carrying out the foregoing advantages consists in the novel construction, combination and arrangement of parts hereinafter described, pointed out in the appended claims and illustrated by the accompanying drawings.

In the accompanying drawings, in which similar reference characters designate corresponding parts:

Figure 1 is a cross-sectional view, on the

line 1—1 of Fig. 2, of a pinch-frame for mine tunnels.

Figure 2 is a side elevation of the same.

Figure 3 is a detail perspective of a saddle forming a part of the joint.

Figures 4, 5 and 6 are detail perspective views, respectively, showing ends of longitudinal and transverse girders and of a column shaped to form the joint.

Figure 7 is a detail sectional view on the line 7—7 of Fig. 1, the chair being shown in full lines.

While the invention is particularly shown and described as being applied to pinch-frames for mine tunnels, yet it is obvious that the joint can be employed in other heavy framework construction.

Referring to the drawings in detail, 10 designates the columns, 11 the longitudinal floor girders, 12 the upper longitudinal 75 girders and 13 upper cross girders of a generally rectangular frame particularly adapted to tunnel reinforcement. The joint between the lower ends of the columns 10 and the longitudinal floor girders 11 is the same as the joint disclosed in my former Patent 1,296,574, of March 4, 1919, except that a chair 14 is interposed between the crown of each girder and the web of the column seated on the girder.

The joints at the corners of the frame between the columns, and the upper longitudinal and cross girders are the same, and a description of one will suffice for all. The web 15 of the column 10 (Fig. 6) is completely cut away at the upper part between the flanged sides 16 to form the upper transverse abutment 17 at the remaining upper edge of the web. In the upper parts of the opposite flanged sides 16 are the vertical slots 18 extending from the seat 17 through the ends of sides, the width of the slots being the same as the thickness of the web and the inner ends of the seats being coincident with the upper abutment 17. In the upper part of the web 15 is the median longitudinal slot 19 extending through the seat or abutment 17. The web at the inner end of slot 19 provides a lower transverse seat or abutment 19'.

The end of the longitudinal girder 12 (Fig. 5) forming part of the joint is shaped to fit the upper part of the column 10. The upper and lower flanged sides 20 of the girder are notched, as at 21, in both edges 110

to fit the inner faces of the flanged sides 16 of the column 10, the web of the girder fitting the slot 19 of the column. The end of the girder is seated in the upper part of the column with the top of the girder flush with the abutment 17 of the column. The web of the girder extends into the slot 19 of the column and the lower edge of the web and the under side of the girder rest 10 on the chair 14 seated in the lower end of the slot 19. The end of the girder engaging opposite sides of the web 15 of the column holds the girder against longitudinal displacement with relation to the column. 15 Also engagement of the under side of the girder with the chair 14 seated on the web of the column prevents downward displacement of the girder.

The end of the transverse girder 13 (Fig. 4) forming another part of the joint is shaped to fit the upper part of the column 10 above the longitudinal girder 12. The opposite edges of the upper and lower flanged sides of the transverse girder, adjacent to the end, are notched, as at 22, to admit the flanged sides 16 of the column. Fitted in place, the web 23 of the transverse girder fits the slots 18 in the opposite flanged sides of the column and the lower 30 flanged side of the girder rests on the top of the longitudinal girder 12 and also on the abutment 17 at the upper end of the web 15 of the column. The flanged sides 16 of the column extend through the slots 22 in the 35 opposite flanges of the upper and lower sides of the transverse girder. By this engagement of the transverse girder and the column, the two are firmly locked together against relative lateral movement and the girder is held against longitudinal and vertical movement with respect to the column.

The chair 14 (Fig. 3) seated between each end abutting the upper and lower longitudinal girders comprises a bearing plate 24 45 to contact with the girder and a web 25 notched at 26 to fit over the transverse edge of the web of the column. In the opposite edges of the bearing plate are the notches 27 to fit the vertical edges of the column 50 web. The chair is seated in the column, in the slot 19, Fig. 6, for an instance, with the vertical edges of the slot extending through the notches 27 and the notched web 25 of the chair straddling the web of the 55 column at the inner end of the slot 19. The chair serves to distribute the load between the girder and the transverse abutment formed on the edge of the column web.

What I claim is:

1. The combination of a column having a web and flanged sides at each edge of the web, with girders interlocked with the column, said column at the interlock having its web cut away between the flanged sides to 60 form an upper transverse abutment, the web 65

also having a median longitudinal slot to form a lower transverse abutment, one of the girders being seated on the lower abutment and the other girder being seated on the upper abutment. 70

2. The combination of a webbed column with girders angularly disposed to each other and interlocked with the column, one of said girders being imposed on the other, said column at the interlock having its web 75 cut away to form inner and outer abutments, the lower girder being seated on the inner abutment and the upper girder being seated on the outer abutment.

3. The combination of a column having 80 a web and flanged sides at each edge of the web, with webbed girders having flanged sides, said column having its web cut away 85 to form inner and outer abutments, the flanged sides of the column having longitudinal slots extending outward from the outer abutment, said girders being angularly disposed to each other with one disposed on the other, the lower girder being seated 90 on the inner transverse abutment and the upper girder seated on the upper transverse abutment, the web of the upper girder registering with the longitudinal slots in the flanged sides of the column, and the flanged 95 sides of both girders being notched and slotted to admit the flanged sides of the column. 100

4. The combination of a column with longitudinal and transverse girders interlocked with the column, the column and both girders being formed each with a web and flanges on both sides at each edge of the web; said column at the interlock having its web cut away between the ends of the flanged sides to provide an upper transverse abutment at the end of the web inset from the extremities of the flanged sides, the web of the column having a median longitudinal slot extending through the upper transverse abutment and providing a lower transverse abutment in the web at the lower end of the slot, and the flanged sides of the column having median longitudinal slots extending through their ends to the upper transverse abutment; said longitudinal girder 105 at the interlock extending between the flanged sides of the column with its web registering with the median longitudinal slot in the column web, the web of the longitudinal girder being seated on the lower transverse abutment of the column web; and said transverse girder at the interlock being imposed on the longitudinal girder and the outer transverse abutment and having its web registering with the longitudinal slots 110 in the flanged sides, the flanges of the girders being notched to admit the flanged sides of the column. 115

In testimony whereof I affix my signature.
WESLEY WAIT.
